COMBINED TOILET SEAT AND LID

Sylvanus Carl Ring, Olney, Ill.

Application February 26, 1954, Serial No. 29,240

Term of patent 14 years

(Cl. D4—5)

To all whom it may concern:

Be it known that I, Sylvanus Carl Ring, a citizen of the United States of America, residing at Olney, in the county of Richland and State of Illinois, have invented a new, original, and ornamental Design for a Combined Toilet Seat and Lid, of which the following is a specification, reference being had to the accompanying drawings, forming a part thereof.

In the drawings:

Figure 1 is a top plan view of a combined toilet seat and lid, embodying my new design with the lid thereof being in open position.

Figure 2 is a front view of the combined toilet seat and lid shown in Figure 1 with the lid in the open position.

Figure 3 is a side view with the lid in open position.

Figure 4 is a top plan view with the lid in closed position.

Figure 5 is a side view with the lid in closed position.

Figure 6 is a bottom plan view the lid being in closed position.

Figure 7 is a front view with the lid in closed position.

I claim:

The ornamental design for a combined toilet seat and lid, as shown.
